DESIGN FOR A LUNCH BOX OR SIMILAR ARTICLE

Everett Worthington, Scarsdale, N. Y., assignor to American Can Company, New York, N. Y., a corporation of New Jersey

Application May 14, 1938, Serial No. 77,198

Term of patent 14 years

To the Commissioner of Patents:

Be it known that I, Everett Worthington, a citizen of the United States, residing at 15 Oak Lane, village of Scarsdale, county of Westchester, and State of New York, have invented a new, original, and ornamental Design for a Lunch Box or Similar Article, of which the following is a specification, reference being had to the accompanying drawing, forming a part thereof.

Figure 1 is a perspective view of a lunch box or similar article showing my new design.

The reverse side of the lunch box is similar to the appearance of the article as viewed in the drawing.

I claim:

The ornamental design for a lunch box or similar article, as shown and described.

EVERETT WORTHINGTON.
